UNITED STATES PATENT OFFICE.

PAUL F. COX, OF CHICAGO, ILLINOIS, ASSIGNOR OF ONE-HALF TO JOSEPH L. COX, OF CHICAGO, ILLINOIS.

PRINTING PRESS.

Application filed December 13, 1922. Serial No. 606,641.

To all whom it may concern:

Be it known that I, PAUL F. Cox, a citizen of the United States, residing at Chicago, in the county of Cook and State of Illinois, have invented certain new and useful Improvements in Printing Presses; and I hereby declare that the following is a full, clear, and exact description thereof, reference being had to the accompanying drawings, which form part of this specification.

This invention relates to improvements in flat-bed web perfecting printing presses in which the web is printed by means of traveling (oscillating) impression cylinders from flat forms of type or plates, resting upon stationary beds; while the cylinders are moving in one direction; said cylinders returning over the beds out of contact with the printing forms, to give time for the intermittent spacing and feeding of the web of paper. In such presses the impression cylinders are preferably raised and held "off impression" upon one stroke, so as not to contact the printing forms; and are then lowered down to bearers, or printing line, and held firmly "on impression" during the return stroke of such cylinders.

The principal object of the present invention is to provide a novel simple mechanism for operating the web compensating looping rollers. More specifically the invention consists in providing a cam bar, moved in unison with and by the cylinder crossheads, for operating such looping rollers. By this cam bar the operation of the web looping rollers is controlled in proper time with the printing and feeding apparatus (in a single acting press) without requiring any extra gearing or shafting or bars, and the web looping mechanism is economical in construction and can be easily repaired or replaced.

In the embodiment of the invention shown in the drawings the cam bar for operating the looping rollers is attached to one of the reciprocating crossheads by which the cylinders and inking rollers are moved back and forth over the beds; the cam bar being located in the most convenient and accessible position for inspection and attachment coacting with an arm connected with the looping roller supports and by which the latter are oscillated to move the rollers in the proper time and manner to cause the de-

sired alternate well and shift of the web over the beds by the looping rollers during the reciprocations of the cylinders.

While the invention is primarily designed for use in a web perfecting press, it is applicable to single acting presses; and to other types of machines in which traveling cylinders are employed which are to be "thrown off impression" on one stroke and "thrown on impression" on the return stroke.

I will explain the invention with reference to the accompanying drawings which illustrate so much of a web perfecting press as will enable the invention to be clearly understood; and summarize in the claims the essentials of the invention, and the novel features of construction, and novel combinations of parts, for which protection is desired.

In the drawings:

Fig. 1 is a partial side elevation of a web printing press showing my novel mechanism for actuating the web looping rollers.

Fig. 2 is a detail view of part of the web feeding devices.

Fig. 3 is a diagrammatical longitudinal section of such press showing the looping mechanism and cam.

Figs 4 and 5 are enlarged detail views of the web looping devices.

In the drawings 1 and 1^a designate parallel type beds arranged one over the other in a suitable main frame. Cooperating with bed 1 is a traveling impression cylinder 2, and cooperating with bed 1^a is a traveling impression cylinder 2^a. These cylinders are mounted in bearings in crossheads 3 which are guided in longitudinal guide ways 4^x in the sides of the press frame. The crossheads 3 are reciprocated longitudinally of the guideways 4 so as to move the cylinders 2 and 2^a back and forth over the beds by any suitable means, preferably by means of pitmen 3^a connecting the crossheads 3 with crank gears 4, which may be operated by any suitable mechanism.

The cylinder 2 is shown as journaled in eccentric bearings 5^x on the cross head, and the cylinder 2^a in eccentric bearings 5^a_x on the crosshead. Such bearings are well known and are preferably constructed as shown in my application #6603, filed August 27, 1921 Serial #495,872 and needs no further description herein.

The general construction and arrangement of such machine and of the aforesaid parts are well known and need no further detailed explanation herein.

5 In the press shown the cylinders are "on impression" during one stroke, and "off impression" during the other stroke of the crossheads.

In the press shown the web *w* is led from 10 the roll *W* under an idler guide roller *g* to and between the infeed devices which consist of a roll 5 mounted upon the shaft 4^a carrying the crank gears 4; and a set of endless tapes 5^b running over guide rollers 5^c 15 and cooperating with the roll 5 to infeed the web in the usual manner. This roll 5 is driven by and in unison with the main shaft 4^a, as hereinafter described. From roll 5 the web *w* is led under guide roller *g'* to a guide 20 roller *g²*; and then back over a looping roller 6^a rotatably mounted in one end of oscillating arms 6 mounted on a rock shaft 6^c suitably journaled in the main frame and operated as hereinafter described.

25 From looping roller 6^a the web is led inward over the bed 1^a to and over a guide roller *g³* mounted on the crossheads adjacent cylinder 2^a and thence up over a guide roller *g⁴* mounted on the crossheads beside cylinder 30 2^a; thence out over a stationary guide *g⁵* mounted on the rear end of the frame; thence up over a roller *g⁶* mounted on the frame; thence inwardly to and over a roll *g⁷* mounted on the crossheads adjacent cylinder 35 2; thence down under cylinder 2 and up over a guide *g⁸* mounted on the crossheads beside cylinder 2; thence forward to and around a looping roller 6^b mounted on the upper ends of the arms 6; thence back under 40 a guide roller *g⁹*; thence to and over an adjustable tensioning roller 7; thence to the delivery roll 8.

The delivery roll 8 is mounted on a shaft 8^a journaled in the side frames of the machine, and driven as hereinafter described. With roll 8 cooperate endless tapes 8^b running over guide rollers 8^c in the usual manner. From roll 8 the web *w* passes out to the folding and delivering devices, not 50 shown.

As shown the infeed roll 5 is rotatably mounted upon the shaft 4^a carrying the crank gears 4 and which shaft is driven from the main shaft 9 by a gear 9^a meshing 55 with gears 4, as shown. The shaft 4^a may be driven in any other desired manner. The roll 5 may be locked to the shaft 4^a, so as to rotate in unison therewith, by any suitable means. For example, a dog or pawl 5^x attached to one end of the cylinder can be engaged with a notch 4^b in the shaft 4^a (Fig. 2) so that the roll will always be locked to the shaft in the same rotatorial position; but when it is desired to thread the press, 60 roll 5 can be freed from the shaft 4^a by dis-

engaging the dog 5^x therefrom, and then the feed roll may be turned on the shaft 4^a to infeed with web in threading up the press.

The delivery roll 8 is preferably driven by and from roll 5. As shown the roll 5 has a gear 5^a attached to one end thereof which meshes with a gear 5^d on geared type drive shaft 5^e journaled in the adjacent part of the press. On shaft 5^e is mounted a bevel gear 5^f and this gear 5^f meshes with a bevel pinion 5^g on a counter shaft 5^h, journaled in suitable brackets attached to the frame. Said counter shaft 5^h extends toward the delivery roll 8 and has a bevel gear 8^h on its upper end meshing with a bevel gear 8ⁱ on the shaft 8^a of the delivery roll 8. The gearing is such that the delivery roll 8 is rotated at substantially the same peripheral speed as the infeed roll 5, or slightly faster so that the web *w* will be fed into and out of the press at the proper speed during the operation thereof.

In threading the press the feed roll 5 is disengaged from the shaft 4^a and then by applying a wrench or crank (not shown) 90 to the squared end 8^f of shaft 8 (Fig. 1) the feed and delivery rolls 5 and 8 may be operated manually, as desired, to feed in and out the web until the press is properly threaded. When the press is threaded and ready for operation the roll 5 is locked to the shaft 4^a by dog 5^x (Fig. 2) so as to rotate therewith, and roll 5 will then be driven by the shaft 4^a, and the delivery roll 8 will be driven by the aforesaid counter 100 shaft and gearing from and in unison with the roll 5. The feed roll is driven in exact unison with the reciprocation of the cylinders, and the rotation of the gears 4 and gearing for driving the infeed roll is not 105 required, and the delivery roll is driven by and from the feed roll.

The levers 6 are provided with arms 6^d to which are connected rods 6^e (Figs. 4 and 5) which extends through eyes 6^f on the lower ends of brackets 6^g attached to the side frame of the press, as indicated in Fig. 4, and a helical spring 6ⁱ is strung on rod 6^e between a collar 6^j on rod 6^e, and the eye 6^f. These springs 6ⁱ normally tend to move the arm 6^d upwardly and rock the shaft 6^c. The collars 6^j are preferably adjustable on the rods 6^e, the upper ends of which are threaded and provided with adjusting nuts 6^k, by which the collars 6^j may be adjusted to vary the tension of the springs 6ⁱ, as desired. I prefer to interpose sleeves 6^l between the springs 6ⁱ and the rod 6^e, as shown in Figs. 4 and 5.

On one end of the shaft 6^c is fixedly secured an arm 6ⁿ which projects toward the crossheads and downwardly, and is normally held in its depressed position by a cam bar 6^p attached to the adjacent crosshead 2^a. Arm 6ⁿ is preferably provided with a roller 125

6° engaging bar 6^p. This cam bar 6^p extends parallel with the guideway, and path of movement of the crossheads, and is moved by and with the crossheads. The under side 5 of the cam bar 6^p is so shaped that as the crossheads move inwardly the arm 6ⁿ is depressed, thereby rocking shaft 6^e, against the action of the springs 6ⁱ, and moving the looping roller 6^a to the right and roller 10 6^b to the left, as the crossheads move toward the shaft 4^a.

When the crossheads move away from shaft 4^a the cam bar 6^p is retracted and springs 6ⁱ throw the arms 6^d upwardly, thereby 15 rocking shaft 6^e in the opposite direction and keeping roller 6^b in close contact with the underside of the bar 6^p, and thereby moving the roller 6^a to the left and 6^b to the right, Fig. 1. I preferably provide an annular 20 roller 6^a above roller 6^b, and adjacent the arm 6ⁿ; said roller 6^a contacting with the upper smooth side of the cam bar 6^p and steadyng the movement of said bar and preventing any upward vibration thereof. 25 Roller 6^a may be mounted on a stud 6^c attached to the adjacent side frame; as shown.

The cam 6^p is reciprocated by and with the crossheads and moves in a path of travel 30 parallel with the path of travel of the impression cylinder and causes the looping rollers 6^a, 6^b to properly take up and give out the web during the inward stroke of the cylinders and permits them to give out and 35 take up web during outward movement of the cylinder.

By properly shaping the cam face of cam bar 6^p the operation of the web looping rollers 6^a, 6^b, is effected and controlled in 40 proper time with the printing, feeding, and delivering mechanism (in the single acting press) without requiring any extra gearing or shafting or bars; the cam being operated in perfect time and unison with other mechanisms from the main crank wheel shaft.

The web tensioning roller 7 is mounted on arms 7^a attached to a rock shaft 7^s mounted in the side frames, and to one of these arms is connected a rod 7^b which extends through a bracket 7^c on the main frame, see Fig. 3, and is provided with an adjusting nut 7^d on its outer end. A spring 7^e is interposed between the bracket 7^c and the nut 7^d, whereby the tension of the spring 7^e can be regulated. The spring 7^e normally tends to draw the rod 7^b outward and causes the roller 7 to automatically maintain the desired tension on the web *w* between the infeed roll 5 and the outfeed roll 8.

60 Operation: In the press shown; by disengaging the feed roll 5 from the shaft 4^a rolls 8 and 5 can be operated manually, as described, and the web can be easily threaded through the press. When the press is properly threaded, as indicated in Fig. 2, and

is ready for operation, the roll 5 is locked to the shaft 4^a and the press is then in position for operation. When the cylinders are on impression and moving across the beds 1, 1^a, the web is stopped between the rollers 6^a, 6^b 70 by the action of the looping rollers 6^a, 6^b, which move in opposite directions, one giving out web as required by the delivery, and the other taking up the web fed in by the feed roll, as required by the continuous infeed and outfeed of the web. After the cylinders have cleared the forms and are off impression, the web is shifted forward by the combined action of the looping rollers, giving out and taking up web, and the 80 continuous action of the outfeed and delivery mechanisms; these operations are well understood in the art and need no detailed explanation herein.

What I claim is:

1. A traveling cylinder web printing press having a reciprocating cylinder, and means for reciprocating the cylinder; a device for looping the web; a cam moving with the cylinder, and means controlled by the said cam for actuating the looping device.

2. A traveling cylinder web printing press having cylinders, means for reciprocating the cylinders; and devices for looping the web; a cam moving with the cylinders; and means controlled by said cam for actuating the looping device.

3. In a flat bed web printing press having a traveling impression cylinder, means for feeding and delivering the web, and a web 95 looping device; a cam member reciprocated with the cylinder for operating the said looping rollers.

4. In a flat bed web printing press having traveling impression cylinders, means for 105 feeding the web, means for delivering the web, and movable looping rollers; a cam member reciprocated by and with the cylinders for operating the said looping rollers.

5. In a traveling cylinder web printing 110 press having reciprocating cylinders, web feeding, web delivering, and web looping devices; of a cam traveling with the cylinders and adapted to impart motion to and control the operation of the web looping devices.

6. In a traveling cylinder web printing press having reciprocating cross heads, means for imparting motion to the cross heads, web feeding and delivering mechanism; and web looping devices; a cam member connected with and operated by the cross heads, and devices controlled by said cam for operating the looping devices.

7. In a web printing press of the character specified having a bed, a co-acting cylinder, cross heads for operating the cylinder, and web feeding and web delivering mechanisms, a web looping device mounted in the press, rock arms carrying the web looping device, and a cam traveling with the cross heads and

adapted to cause said arm to move the looping device.

8. In a web printing press of the character specified having beds, cylinders, reciprocating cross heads for operating the cylinders, web feeding and web delivering mechanisms and web looping devices, of a rock arm for carrying the web looping devices, springs for operating the arm in one direction, and a cam traveling with the cylinder and engaging said arm to move the looping devices against the action of the spring.

9. In a web printing press having a bed, reciprocating cross heads, a cylinder journaled in said cross heads and adapted to be reciprocated over the bed; web feeding and delivering mechanisms; web looping device interposed between the web feeding devices and the bed, and a web looping device interposed between the delivery and the bed, a cam connected to and traveling with the cross heads, and means controlled by said cam for operating both said looping devices, substantially as described.

10. In mechanism as set forth in claim 9, the web looping device comprising a rock shaft, arms mounted thereon, upper and lower rollers carried by said arm, spring means for rocking the shaft in one direction, and an arm on said shaft adapted to be engaged by said cam to rock the shaft in opposition to the spring means.

11. In a web printing press having stationary beds, reciprocating cross heads, cylinders mounted in said cross heads adapted to be reciprocated over the beds, web feeding and delivering mechanisms, and a web looping roll between the web feeding devices and the beds, and a web looping roller interposed between the delivery and the beds; of a cam connected to and traveling

with the cross heads and means controlled by said cam for operating both said looping devices, substantially as described.

12. In mechanism as set forth in claim 11, the web looping devices comprising a rock shaft, arms mounted thereon, upper and lower rollers carried by said arm, spring means for rocking the shaft in one direction, and an arm on said shaft adapted to engage said cam to rock the shaft in opposition to the spring.

13. In combination with beds, cylinders co-acting therewith and web feeding and delivery mechanism; of web looping devices comprising a rock shaft, arms mounted thereon, upper and lower rollers carried by said arm, spring means for rocking the shaft in one direction, an arm on said shaft and a reciprocating cam rod connected with and actuated by the cross heads and adapted to engage said roller to rock the shaft in opposition to the spring.

14. In combination with beds and coacting cylinders, cross heads for operating the cylinders, a shaft, crank gears mounted thereon and pitmen connecting said gears to the cross heads to operate the latter; of a feed roll, a delivery roll and gearing between the feed roll and the delivery roll; of web looping devices comprising a rock shaft, arms mounted thereon, upper and lower rollers carried by said arm, spring means for rocking the shaft in one direction, an arm on said shaft and a reciprocating cam rod connected with and actuated by the cross heads and adapted to engage said roller to rock the shaft in opposition to the spring.

In testimony that I claim the foregoing as my own, I affix my signature.

PAUL F. COX.
